UNITED STATES PATENT OFFICE.

JAMES J. SCHEURICH, OF JOPLIN, MISSOURI.

GAS REGULATOR.

Application filed December 10, 1921. Serial No. 521,558.

To all whom it may concern:

Be it known that I, JAMES J. SCHEURICH, a citizen of the United States, residing at Joplin, in the county of Jasper and State of Missouri, have invented certain new and useful Improvements in Gas Regulators, of which the following is a specification, reference being had to the accompanying drawings.

- 10 This invention relates to pressure apparatus, particularly to regulators, and has for its object the provision of a novel device which will automatically regulate the pressure or flow of gas and reduce it from a high 15 to a low pressure for use wherever desired, the device being intended primarily for use in flour mills for regulating the pressure of chlorine gas, though no restriction as to its use is intended for the reason that it is well 20 adapted to be employed in a wide variety of arts and for a multiplicity of purposes.

An important object is the provision of a gas regulator of this character which is readily adjustable whereby to control the pressure or flow and maintain it at a uniform degree, the adjusting means being furthermore so constructed and arranged as to be readily accessible without disassembling the device.

Another and more specific object is the 30 provision of a regulator for this purpose which embodies a flexible diaphragm having operative connection with a control valve, means being provided for applying air pressure against one side of the diaphragm for the purpose of varying its sensitivity and opposing the action of the gas under pressure.

An additional object is the provision of a device of this character which will be simple 40 and inexpensive in manufacture, easy to install, automatic in operation, positive in action, durable in service and a general improvement in the art.

With the above and other objects and advantages in view, the invention consists in the details of construction to be hereinafter more fully described and claimed and illustrated in the accompanying drawings, in which:

50 Figure 1 is a plan view of the device with parts broken away and in section;

Figure 2 is a sectional view therethrough on the line 2—2 of Figure 1; and

55 Figure 3 is a cross sectional view on the line 3—3 of Figure 1.

Referring more particularly to the drawings, I have shown my device as comprising a circular casing which in actual practice is formed of two sections 10 and 11, formed with outwardly extending flanges 12 and 13, respectively, secured together as by means of bolts 14. The section 11 is formed with an inwardly extending flange 11^a to which is secured, as by means of bolts 15, an outwardly extending flange 16 formed on a cover 17. 60

Formed within the section 11 and extending diametrically thereacross is a bar 18 which is formed with a longitudinally extending channel 19 which extends through one side of the section 11 and which constitutes the high pressure feed to the device. Leading into the outer end of this channel is a split pipe 20 leading from any suitable source of gas under more or less high pressure and associated with this pipe 20 is a 70 conventional pressure gauge 21. At its center the bar 18 is formed with a small lateral passage 22 which leads into a threaded recess 23 within which is screwed a plug 24 having a bore 25 registering with the passage 22 and terminating at its outer end in a valve seat. 75 Leading through the cover 17 is a pipe 26 which leads to a conventional pressure gauge 27 and with which is connected a pipe 28 for conducting the gas to the place where it is 80 to be used.

Secured between the flanges 12 and 13 is a flexible diaphragm 29 which divides the interior of the entire casing into two chambers 30 and 31. Disposed against one side 90 of this diaphragm is a plate 32 carrying a threaded stub 33 which passes through the diaphragm and through a plate 34 disposed against the other side thereof. Engaged upon the stub 33 is a nut 35 which holds the 95 plates 32 and 34 properly clamped upon the diaphragm. Carried by the plate 32 are spaced parallel posts 36 which are disposed at opposite sides of the bar 18 and which have threaded ends 37 which are passed 100 freely through a cross bar 38 through the center of which is screwed a valve 39 terminating in a conical point 39^a cooperating with the valve seat formed at the end of the bore 25. The bar 38 is held in adjusted 105 position upon the posts 36 by means of two nuts 40 threaded upon each post and engaging against opposite sides of the bar. The valve 39 is itself adjustable and has its upper end formed with a slot within which 110

may be engaged a screw driver or the like for effecting adjustment and the cover 17 is formed centrally with a threaded hole 41 in which is screwed a plug 42 which is removable to permit access to the valve, a screw driver or the like being insertable through this hole 41.

Leading into the casing section 10, that is into the chamber 30, is a pipe 43 leading from any suitable source of compressed air and associated with this pipe is a conventional gauge 44.

Assuming that the device has been constructed and assembled as above described, the operation is as follows: The gas under high pressure is introduced through the pipe 20 and will pass through the channel 19, passage 22 and bore 25 into the chamber 31. Any desired degree of pressure is applied to the chamber 30 through the compressed air conducting pipe 43. The gas within the chamber 31 of course passes out through the pipe 28 to wherever it is to be used. When the gas within the chamber 31 exerts a certain predetermined pressure governed by the adjustment of the parts, the diaphragm 29 will bow against the resistance of the pressure within the chamber 30 and this will result in movement of the posts 36 carrying the cross bar 38 which in turn carries the valve 39 and the valve will then seat and close the outer end of the bore 25 and consequently cut off the inlet of high pressure gas until the pressure within the chamber 31 is reduced to the proper degree. This action is entirely automatic and will result in producing a gas flow through the pipe 28 of absolutely uniform pressure. The sensitiveness of the device is readily regulatable by adjusting the valve 39 and by varying the pressure within the chamber 30 so as to meet any and all conditions which may arise.

From the foregoing description and a study of the drawings it will be apparent that I have thus provided a simply constructed and consequently inexpensive pressure regulator which will be entirely automatic in action and which will require no attention after the parts have once been set or adjusted to result in the proper flow. It is to be noted that while the device is described as being for regulating gas pressure it might also be used for regulating the pressure of a current of liquid, and in the event that the device is used for handling chlorine in the art specified, it is advisable that the parts exposed to the action of the gas be constructed of bronze or other suitable non-corrosive material. It is also to be observed that the plug containing the valve seat may be removed in case of wearing out of the valve seat so that the device may be made as good as new even after long use. Owing to the simplicity of the con-

struction and the fewness of the parts, it is apparent that there is practically nothing to get out of order and that the device should consequently have a long life and satisfactorily perform all the functions for which it is intended.

While I have shown and described the preferred embodiment of the invention it is, of course, to be readily understood that I reserve the right to make such changes in the form, construction and arrangement of parts as will not depart from the spirit of the invention or the scope of the subjoined claims.

Having thus described my invention, I claim:

1. A device of the character described, comprising a sectional casing, a flexible diaphragm therein dividing the interior into two chambers, means for applying air pressure within one chamber, a bar integral with one section extending across the other chamber and formed with an inlet channel for fluid under high pressure terminating in a valve seat communicating with the second named chamber, and a valve carried by the diaphragm and cooperating with said seat for closing the same when the pressure within the second named chamber overbalances that in the first named chamber, said valve consisting of a screw having a conical point, and the casing being provided opposite said valve with an opening closed by a plug removable to permit access to the screw for adjusting the same.

2. A device of the character described, comprising a sectional casing, a flexible diaphragm therein dividing the interior into two chambers, means for applying air pressure within one chamber, a bar integral with one section extending across the other chamber and formed with an inlet channel for fluid under high pressure terminating in a valve seat communicating with the second named chamber, and a valve carried by the diaphragm and cooperating with said seat for closing the same when the pressure within the second named chamber overbalances that in the first named chamber, said valve consisting of a supporting plate secured to the diaphragm, posts carried by said plate and straddling said bar, a cross member connecting the posts, and a screw adjustable through said cross member and having a conical end co-operating with said valve seat.

3. A device of the character described comprising a casing formed of sections, a diaphragm clamped between said sections and dividing the interior of the casing into two chambers, means for supplying pressure to one of the chambers, a bar within the other chamber formed with an inlet channel for fluid under pressure and formed with a lateral passage leading into

a recess, a threaded plug within said recess having a bore registering with said passage and terminating in a valve seat, an outlet pipe connected with the second named chamber, a plate carried by the diaphragm, spaced posts extending from the plate and straddling the bar, a cross member having an adjustable screw mounting upon said posts, and a valve threaded through said cross member and co-operating with said seat. 10
5 In testimony whereof I hereunto affix my signature.

JAMES J. SCHEURICH.
